UNITED STATES PATENT OFFICE.

GEORGE ALBERT HARPER, OF SHREVEPORT, LOUISIANA.

DENTAL IMPRESSION TRAY.

Application filed July 25, 1923. Serial No. 653,735.

To all whom it may concern:

Be it known that I, GEORGE A. HARPER, a citizen of the United States, and a resident of Shreveport, in the parish of Caddo and 5 State of Louisiana, have invented certain new and useful Improvements in Dental Impression Trays, of which the following is a specification.

My present invention relates generally to 10 artificial dentures and more particularly to an impression tray for taking a lower impression in making artificial dentures, my object being the provision of a tray adjustable for the purpose of fitting the lower 15 jaw, which may be utilized with ease, facility and effectiveness and in which the adjustable parts are separable to facilitate the movement from the mouth and may be easily and quickly reassociated and adjusted to 20 perfect adaptation to the impression after removal.

In the accompanying drawing illustrating my present invention and forming a part of this specification,

25 Figure 1 is a perspective view looking from the underside of my improved impression tray,

Figure 2 is a top plan view of the tray,

Figure 3 is an end view thereof,

30 Figure 4 is a side view of one of the sections removed, and

Figure 5 is a partial side view of the other section.

Referring now to these figures my improved lower impression tray is like the usual tray generally of U-shape and is of channel form and is in accordance with my invention divided at an approximately central point into two curved side sections 10 and 11 whose inner or meeting ends are joined by virtue of certain connections including extensions 12 carried by the inner end of the section 10 as shown in Figure 5 which are spaced apart and conformably 45 curved to overlap the adjacent end of the section 11. These extensions 12 of the section 10 are moreover disposed upon opposite sides of an upright semicylindrical socket member 13, adjacent to which the 50 end of section 10 has a projecting wing 14 apertured as at 15.

In order to cooperate with the section 10, section 11 has at its inner meeting end an upright stud 16 adapted to movably interfit the socket 13 of section 10 providing for the completion of a vertical pivotal con-

nection by the use of a short readily removable sleeve 24 which telescopes the socket 13 and stud 16 as in Figures 1 and 2. The section 11 is provided adjacent to the 60 stud 16 with an outstanding wing 17 apertured as at 18 and adapted to oppose the wing 14, it being noted that the apertures 15 and 18 align when the sections are in properly 65 assembled relation as in Figures 1 to 3 inclusive so as to receive therethrough an adjusting screw 19. This adjusting screw is threaded through both of the openings, and the wings being somewhat flexible, adjustment of the screw permits the two sections 70 10 and 11 to be secured adjustably with their outer ends spaced apart more or less within certain limits. It will be noted from Figures 2 and 3 in particular that the wing 17 of section 11 is offset at its inner portion 75 so as to permit one of the overlapping extensions 12 of section 10 to project onto the adjacent portion of the section 10 and it will be noted from Figures 1, 2 and 3 that the two wings 14 and 17 when connected in adjustable relation by the screw 19, form a handle by means of which the tray as a whole may be manipulated in the mouth. It will furthermore be obvious that it is simply necessary to withdraw the adjusting screw 19 and remove the pivot holding sleeve 24 in order that the two sections 80 10 and 11 may be readily disassociated and removed easily and quickly from the mouth one at a time subject to easy and quick re-adjustment and reassembly in perfect adaptation to the impression material after the latter is withdrawn.

In further accordance with my invention the sections 10 and 11 are provided at their 95 free ends and at their inner sides with wings 20, each having a longitudinal slot 21 and each adjustably mounted on a stud 22 projecting through the slot thereof for the reception of a clamping nut 23. These wings 100 which are located upon the inner sides of the ends of the channel of the tray serve to hold and press the impression material carried by the tray in its practical use closely against the inner portion of the jaw, and 105 for this purpose their angular relationship to the tray as well as the extent of their projection beyond the tray ends may be easily adjusted and controlled.

It is thus obvious that my improved tray 110 is not only adjustable to fit jaws of different sizes so as to avoid the necessity of a

multitude of different size trays, but it is obvious that such adjustment may be quickly and easily effected and that the wings also are adjustable making it possible to press the impression material or compound firmly against the jaw in order to assure a more adaptable impression and better fitting plate.

I claim:

10. 1. A dental impression tray of approximately U-shape, divided substantially at the center thereof and including a pair of side channels having pivot forming members at their inner meeting ends on which they are adjustable with respect to one another, said pivot forming members being detachably engageable with one another, and means to adjust and secure the two side sections in adjusted position.
15. 2. A dental impression tray including a pair of curved side channels in endwise abutting relation, one of said channels having an upright stud and the other having an upright semicylindrical socket, said stud and socket being located at the meeting ends of the channels and forming a detachable pivotal connection therefor, detachable means to normally hold the stud within the socket and a screw member for adjusting said channels and holding the same in adjusted position.
20. 3. A dental impression tray including a pair of curved side channels in endwise abutting relation, one of said channels having an upright stud and the other having an upright semicylindrical socket, said stud and socket being located at the meeting ends of the channels and forming a detachable pivotal connection therefor, said channels having adjacent to their abutting ends outstanding opposed wings provided with

apertures, and a connecting screw extending through said apertures.

4. A dental impression tray of approximately U-shape and of channel form, a pair of adjustable pressure wings disposed opposite one another at the inner sides of the free ends of said tray, and supports for said wings upon which the latter are movable lengthwise of the tray sides and rotatable as described.

5. A dental impression tray of channel form having inwardly projecting studs adjacent to its free ends, a pair of pressure wings having lengthwise slots through which said studs extend, and clamping nuts threaded on the studs as and for the purpose described.

6. A dental impression tray including a pair of curved side channels in endwise abutting relation, one of said channels having an upright stud and the other having an upright semicylindrical socket, said stud and socket being located at the meeting ends of the channels and forming a detachable pivotal connection therefor, detachable means to normally hold the stud within the socket, and detachable means to connect and support the pivoted channels in adjusted position.

7. A dental impression tray including a pair of curved side channels in endwise abutting relation, one of said channels having an upright stud and the other having an upright semicylindrical socket, said stud and socket being located at the meeting ends of the channels and forming a detachable pivotal connection therefor, and a sleeve telescoping the socket and the stud therein to hold the same in pivotal relation and readily removable therefrom.

GEORGE ALBERT HARPER.
